VACUUM SWITCH

Howard F. Anderson, Torrington, Conn.

Application June 2, 1934, Serial No. 728,653

7 Claims. (Cl. 200—30)

This invention relates to electric vacuum switches, and more particularly to a vacuum switch adapted to be used in conjunction with the ignition system of an internal combustion engine.

One object of this invention is to provide a vacuum switch of the above nature which will be particularly adapted to operate as an interrupter in the ignition system of a multi-cylinder internal combustion engine.

A further object is to provide an interrupter switch of the above nature in which the contact points are completely sealed within a vacuum chamber, and in which one of said points is mechanically operated from the exterior of said chamber, thereby reducing arcing and consequent oxidation and pitting of the points, and eliminating the danger of explosions or fires which were formerly caused when open contact points were used.

A further object is to provide a switch of the above nature in which the "breaking" distance between the points is reduced, thus enabling the switch to operate faster and with a smaller "electrical lag."

A further object is to provide a vacuum switch of the above nature which will be simple in construction, easy to install and manipulate, compact, and very efficient and durable in use.

With these and other objects in view there have been illustrated on the accompanying drawing two forms in which the invention may be conveniently embodied in practice.

In the drawing:

Fig. 1 represents a horizontal sectional view through the electric vacuum switch as it appears when installed upon a distributor base.

Fig. 2 is a plan view of the same on a reduced scale, and showing a condenser connected thereto.

Fig. 3 is a diagrammatic view of the ignition system of an internal combustion engine with the vacuum switch shown included in the circuit thereof.

Fig. 4 is a horizontal sectional view taken through a modified form of vacuum switch.

Referring now to the drawing in which like reference numerals denote corresponding parts throughout the several views, the numeral 10 indicates a cup-shaped container for inclosing the vacuum switch, said container being preferably made cylindrical in shape and of suitable impervious metal, such as phosphor bronze. The open end of the container 10 is closed by a thin metallic resilient diaphragm 11 having a cen-

tral aperture from which extends a drifted neck 12 for flexibly supporting an interrupter lever 13, which is tightly sealed in said neck as by solder. The outer edge of the diaphragm 11 is provided with an upstanding flange 14 which fits over the end of the container 10 and is hermetically tightly sealed thereto, as by the use of solder.

In order to support the container 10 upon a horizontal metallic plate 16, forming part of a distributor head 17, provision is made of a lateral bracket member 15, preferably soldered to said container and attached to said plate 16 by screws 18 (see Fig. 3).

The outer end of the lever 13 is formed with an offset boss 13a having a tapped hole extending therethrough for receiving an adjustable screw 19 having a cam-engaging head 20, said screw 19 being adapted to be locked in adjusted position by a nut 21. The screw head 20 is adapted to normally lie in contact with the periphery 22 of a multi-sided cam 23 which is rigidly mounted on the rotating timing shaft 24 of the distributor head 17.

The inner end of the lever 13 carries a movable contact point 25 which is adapted to intermittently engage a stationary contact point 26 on the container 10 for making and breaking the circuit of the ignition system. As shown in Fig. 1, the movable contact point 25 is detachably secured to the end of the lever 13 for convenience in assembly.

The stationary contact point 26 is integrally formed on the end of an elongated stud 27 mounted in a pair of insulating sleeve bushings 28 and 29 having cooperative engagement on opposite sides of a flattened surface 30 outwardly offset from the wall of the container 10.

In assembling the stud 27 and bushings 28 and 29, a coating of shellac or similar insulating sealing material may be spread between the contacting surfaces of said bushings and stud, and upon both sides of the offset metal surface 30, after which the parts may be tightly clamped together by means of a nut 27a and washer 27b, thus effecting a very tight hermetic seal.

The exterior threaded end of the stationary contactor stud 27 is electrically connected by a wire 31 to a binding post 32 insulated by a non-conducting bushing 16a from the distributor body plate 16, said post 32 being joined as by a conductor 33 to the primary winding 37 of the induction coil 38.

The air is exhausted from the container 10 to a high vacuum, preferably about 740 m. m. of mer-

cury at 60 degrees F. However, it is also within the scope of the present invention to replace the air in the container with a gas which contains insufficient conductive gas ions to maintain an arc between the contactor points 25 and 26 when the circuit is opened. For permitting the air in the container to be thus exhausted or replaced, the container 10 is provided with a tubular pointed nub 34, which is adapted to be permanently sealed, as by fusing, when the proper vacuum has been produced.

In Fig. 3 the electric vacuum switch is shown in operating position in circuit with a conventional form of closed-circuit ignition system. The primary circuit which is indicated by a heavy line, leads from the positive terminal of a battery 35 through a switch 36, the primary winding 37 of the coil 38, through the contact points 25 and 26, the lever 13, the container 10, the body plate 16, which is grounded as indicated by the dotted line 39, the circuit being completed to the negative terminal of the battery 35 through the ground connection 39a.

A condenser 40 is connected at one end 40a to the binding post 32 mounted on the distributor plate 16, the other end 40b of said condenser being connected to said plate 16 as by a bolt 40c.

The secondary circuit is indicated by the light lines shown in Fig. 3, and comprises a winding 41 of fine wire connected to the ground by the wire 41b, the other end of said winding 41 being connected to the center terminal 42 of an insulating distributor head cap 43. The terminal 42 makes contact with a metal spring 44 on an insulated rotating distributor brush 45 supported upon the upper end of the rotor shaft 24.

As shown in Fig. 3, one end of the spring brush 44 when rotated passes close to, but does not touch, a plurality of metal distributor terminals 46 located in the head cap 43 (the number of terminals 46 depending on the number of engine cylinders). The terminals 46 are connected by wires 46a to the heads of the respective spark plugs 47 in the usual manner. The current after jumping the gaps from the brush 45 to the terminals 46 will flow through the wires 46a and jump across the gaps at the points of the spark plugs, from which it will flow through the spark plug sockets 48 to the grounded engine block 49.

50 Operation

The operation of the vacuum switch for interrupting the circuit in the ignition system of an internal combustion engine is as follows:

55 The continuous rotation of the cam 23 of the distributor head 17 moves the lever 13 intermittently about its fulcrum in the drifted neck 12 of the diaphragm 11. This causes the movable contact point 25 to swing back and forth with respect to the stationary point 26, thus making and breaking the electrical contact therebetween without sparking.

Modified form

65 In the modified form of the invention shown in Fig. 4, provision is made of an interrupter rod 50 which operates in the manner of a sliding plunger instead of as a rocking lever, as in the first form of the invention. The rod 50 is hermetically sealed to the neck 12 of the diaphragm 11 as before, and is provided at its outer end with a coaxial adjustable headed screw 51 adapted to be engaged by the rotary cam 23. The inner end 70 of the sliding rod 50 is looped over to form a return bend 52, terminating in a movable contact

75 point 53 which is adapted to intermittently engage with a stationary contact point 54 formed on the inner end 55 of an angular insulated stud 56.

In order to hold the sliding rod 50 in position, provision is made of a U-shaped bracket member 57 secured to the open end of the cup-shaped container 10, said bracket being provided with a central bearing aperture for guiding said plunger rod 50.

One advantage of the present invention is that 10 by enclosing the interrupter switch in a vacuum, the usual separation of .020" between the contact points may be reduced to as low as .005" when breaking the circuit, without injurious sparking.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what 25 is claimed as new, and for which it is desired to secure Letters Patent is:

1. In an electric switch, an evacuated metal container having a flat metal diaphragm on one face thereof, a stationary contact fixed to the 30 inner wall of said container and insulated therefrom, a sealed lever fulcrumed in said diaphragm and carrying a movable contact on its inner end for engagement with said fixed contact, means for connecting said contacts outside 35 of said container in circuit with a multiple ignition system, and means outside of said container for intermittently rocking said lever for continually opening and closing said switch.

2. In an electric switch, an evacuated metal 40 container having a flat metal diaphragm on one face thereof, a stationary contact fixed to the inner wall of said container and insulated therefrom, a sealed lever fulcrumed in said diaphragm and carrying a movable contact on its 45 inner end for engagement with said fixed contact, means for connecting said contacts outside of said container in circuit with a multiple ignition system, and means for intermittently rocking said lever for continually opening and closing said 50 switch.

3. In an electric switch, an evacuated metal container having a flat metal flexible diaphragm on one face thereof, a stationary contact member 55 passing through said container and insulated therefrom, a sealed movable contact rod passing through said diaphragm and electrically connected thereto, said rod carrying a movable contact on its inner end for engagement with said fixed contact, means for electrically connecting said stationary contact member and container in circuit with a multiple ignition system, and means for intermittently moving said rod for periodically opening and closing said switch.

4. In an electric switch, an evacuated metal 65 cup-shaped cylindrical container, a thin metal resilient diaphragm having a central flanged aperture and a peripheral flange fitted over the open end of said container and sealed thereto, a stationary contact member passing through the 70 wall of said container sealed thereto and insulated therefrom, a movable contact rod passing through the flanged aperture in said diaphragm and sealed thereto, said rod carrying a movable contact on its inner end for engagement with said 75

fixed contact, means for electrically connecting said stationary contact member and container in circuit with a multiple ignition system, and means for intermittently moving said rod for periodically opening and closing said switch.

5. In an electric switch, an evacuated metal container having a flat metal diaphragm on one face thereof, a stationary contact fixed to the inner wall of said container and insulated therefrom, a sealed lever fulcrumed in said diaphragm and carrying a movable contact on its inner end for engagement with said fixed contact, means for connecting said contacts outside of said container in circuit with a multiple ignition system, and means for engaging the exterior end of said lever for intermittently rocking said lever for continually opening and closing said switch.

10 6. In an interrupter for a multiple ignition system, a distributor having a timing shaft, a metal base, an evacuated container having grounded

connection to said base, said container having a flat diaphragm on one side and an interior stationary contact insulated therefrom and also having a hermetically sealed movable contact member electrically connected therewith and extending at right-angles through said diaphragm, cam means carried by said timing shaft for periodically moving the movable contact into and out of engagement with said stationary contact, and means for connecting said stationary contact to an inductance.

15 7. In an electric switch, an evacuated container having a thin flat flexible diaphragm on one face thereof, a stationary contact fixed to the inner wall of said container, a movable rod passing through said diaphragm and hermetically sealed therein, said rod carrying a movable contact on its inner end for engagement with said fixed contact, and means for intermittently moving said rod for opening and closing said switch.
